UNITED STATES PATENT OFFICE.

CHARLES HURLEY, OF JERSEY CITY, NEW JERSEY, ASSIGNOR TO CONTINENTAL CAN COMPANY, INC., OF NEW YORK, N. Y., A CORPORATION OF NEW YORK.

LIQUID ATOMIZER.

Application filed November 24, 1925. Serial No. 71,133.

This invention relates to liquid atomizers in which an air current is employed for sucking liquid from a container and then delivering it in atomized form, and more particularly to self-contained insecticide sprayers.

According to the present invention, a sealed liquid container is rigidly attached to the air conduit and normally is at a lower level than the discharge orifice in the end of the conduit. A suction pipe leading from below the surface of the liquid in the container passes upward and terminates substantially opposite the discharge outlet of the conduit. The air current passing through the discharge orifice and over the end of the supply tube causes a suction of liquid into the latter and a discharge of the liquid in particles therefrom.

Such devices have been on the market for a long time, but it has been found with such devices that when the container is heated, the air entrapped in the upper part thereof will cause a sufficient pressure upon the body of the liquid therein to elevate the same in the tube, and provoke an overflow. This results in a waste of liquid and a very disagreeable soiling of the mouth of this tube. Furthermore, such a device has the disadvantage that, if the container and conduit be inverted, the supply tube is no longer beneath the surface of the liquid and the latter cannot pass to the discharge orifice of the air conduit for atomization.

According to the present invention, however, means are provided to eliminate this overflow due to conditions of local heating or barometric variations. Furthermore, the device is capable of operating as an atomizer even when inverted.

The invention is particularly characterized by its simplicity and cheapness of construction. The absence of moving parts prevents failure to operate because of sticking or corrosion. With these and other objects in view, there is shown in the accompanying drawings one form of execution in which the container is rigidly attached to a portable air pump.

Figure 1 is an elevation of the atomizer with parts broken away to illustrate the relation of the various elements.

Fig. 2 is an end view of the same on a somewhat larger scale, with a portion broken away.

Fig. 3 is a fragmentary view similar to Fig. 1, with the atomizer inverted.

In Fig. 3, the device is illustrated as having the air-pump cylinder 10 with the piston 11 therein to be reciprocated by the piston rod 12 which passes through an opening in the rear wall 13 of the pump cylinder and has an operating handle 14 thereon. The front end wall 15 of the pump cylinder 10 has a small discharge conduit orifice 16 thereon.

It will be understood that when the pump handle and piston rod are forced in the direction of the arrow in Figs. 1 or 3, a current of air is delivered through the discharge orifice 16.

A connecting web 17 serves to support a liquid container 18 in rigid relation to the pump cylinder 10. This container 18 is closed and has the hermetically sealed filling cap 19 at its top when resting in a normal position. The supply pipe 20 opens into the container 18 near its bottom when held in a position of normal use, as shown in Fig. 1. It extends through the top of this container and has its end 21 opposite the discharge orifice 16 of the pump cylinder (Fig. 2).

Within the container 18 but very close to its upper wall in the position of Fig. 1 is a vent opening 22 in the pipe 20 which is of much smaller area than the cross section of the pipe 20. It will be understood that the cross section of the pipe 20 is proportioned according to the liquid to be employed and to the quantity of air which may be delivered through the discharge orifice 16: This is well known in the art and has been employed for a long time.

It is preferable to provide a small skirt 23 about the upper end of the tube to catch liquid which may drip therefrom during the atomizing operation, and to support the tube 20 in fixed position. This skirt 23 is maintained a sufficient distance below the end 21 of the tube 20, so that free atomization may occur.

In operation, when the current of air is delivered through the discharge orifice 16 and past the upper free end 21 of the tube 20, the liquid is sucked out of the container 18 through the tube 20, and delivered at its end 21. The air current from the discharge orifice 16 blows this liquid into droplets and forms a fine spray which is projected with considerable force in the desired direction.

When the piston 11 is returned in the opposite direction, the relative air pressure within and without the container 18 balances itself through the pipe. This action is repeated as often as desired.

If for any reason it be desired to invert the atomizer, the liquid will normally be held within the container 18 by the trapping of the air in the upper part of this container. When, however, the air current from the pump cylinder 10 is discharged through the orifice 16, the suction at the end 21 of the pipe 20 will cause the liquid to be sucked down through the small opening 22 into the pipe 20 and delivered at its outer end, so that the spraying action occurs as shown in Fig. 3.

If the device in the upright position be placed upon a radiator or other hot object, the liquid and air within the container will be warmed. The air expands and would normally tend to force the liquid out through the tube 20. According to this invention, however, this air pressure in the upper part of the container 18 is relieved through the vent opening 22 and allowed to escape without causing an overflow. The same action occurs when barometric differences of pressure exist inside and outside of the container 18.

It is obvious that the invention is not limited to the particular form of execution shown, but that any modifications may be made therein within the scope of the appended claims.

I claim:

1. In an atomizer for liquids including a substantially closed container for the liquid to be atomized, a liquid delivery tube open at both ends and passing through the wall of said container and constituting the only

opening of said container while in use, said tube extending substantially across the container to opposite sides thereof, and having a relatively small continuously open aperture through the wall at a point within the container and in close proximity to the point where said tube passes through the wall of said container, and means to create a liquid-delivering suction in said tube and to atomize the liquid delivered at the outer open end thereof.

2. In an invertible atomizer for liquids, an air conduit, a substantially closed container for the liquid to be atomized, a liquid delivery tube passing through the wall of and extending substantially across said container in either position for use, said tube having continuously open apertures into said container adjacent both top and bottom walls thereof in either position for use, said tube also having an opening therein outside said container, and means to hold said tube and said air conduit in fixed relation substantially at a right angle to each other for suction of liquid from said container through said tube and for atomization thereof, said continuously open apertures permitting the atomizer to operate both in normal and inverted positions, said aperture in said tube adjacent the point where said tube passes through said wall serving to permit the balance of the pressure within with that without said container while said container is in the normal position and not in use and being relatively small whereby to prevent the escape of liquid therefrom by gravity when said container is in the inverted position.

In testimony whereof, I affix my signature.

CHARLES HURLEY.
